HAIR CURLING DEVICE

Martha O. Montgomery, Independence, Mo.

Application November 20, 1950, Serial No. 196,643

2 Claims. (Cl. 132—33)

1

This invention relates to a hair curling device including a pair of elements cooperable in their respective actions to permit the user thereof to form a curl, to press the same flatly against the head and to insert a number of conventional bobby pins for holding the curl intact, the primary object being to improve upon the unit disclosed in my co-pending application, Serial No. 88,184, filed April 18, 1949, and now granted as Patent No. 2,535,223.

This is a continuation in part of my said co-pending application and has for its most important object to present a device so formed and arranged as to permit quick and easy removal thereof from the formed curl, clearing the affixed pins, leaving no uncomfortable part of the device within the curl or otherwise affixed to the hair of the user and eliminating all possibilities of entanglement with the hair.

It is an important object of the present invention to provide a hair curling device that includes a pair of relatively slidable members, one of the members being elongated and having a plurality of opposed slots disposed longitudinally adjacent one end thereof, the other member comprising a collar that is frusto-conical to cause all loose strands of hair to slide freely therefrom during use, thereby preventing reveling and snaring of the hair thereabout.

Another important object of the present invention is to provide an elongated member having two pairs of longitudinally disposed slots extending inwardly from one end thereof, there being a collar slidable on the member that is in turn provided with a number of wedge-shaped extensions, defining a slit for each of the slots of the member respectively for receiving a pair of bobby pins in crossed relationship to be affixed to the curl in holding relationship thereto.

Another object of the present invention includes the particular way in which the collar is held against rotative movement with respect to the elongated member upon which the collar is slidably mounted.

Other more minor objects including details of construction will be made clear or become apparent as the following specification progresses, reference being had to the accompanying drawing, wherein:

Figure 1 is a perspective view of a hair curling device made in accordance with my present invention, showing the first step in the use thereof.

Fig. 2 is a perspective view thereof showing the second step in the hair curling operation.

Fig. 3 is a perspective view showing the curl

2

that is formed through use of the unit forming the subject matter hereof.

Fig. 4 is a side elevational view of the hair curling unit per se.

Fig. 5 is an end elevational view thereof.

Fig. 6 is a longitudinal, substantially central, cross-sectional view taken on line VI—VI of Fig. 4; and

Fig. 7 is a transverse, cross-sectional view taken on line VII—VII of Fig. 4 looking in the direction of the arrows.

The hair curling device shown in the drawing, includes an elongated member 10, having slidably mounted thereon a relatively short frusto-conical collar 12. As shown particularly in Figs. 5 and 7, the transverse, cross-sectional contours of the member 10 and the collar 12, are preferably circular, but not necessarily so and other configurations may well serve the purposes hereof.

10 The member 10 may well be solid substantially the entire length thereof if desired, but for the interest of lightness, the same has been illustrated as tubular, one end thereof serving as a finger grip and provided with a knurled annulus 18 to prevent slippage. Any metallic substance may be used to form the member 10 as well as the collar 12, but it has been found that a plastic material is quite suitable, particularly for collar 12, because of its lightness, cheapness and attractiveness.

20 One open end of the member 10 opposite to the grip 18 is provided with a plurality of longitudinally disposed, inwardly extending slots, there being two pairs of opposed slots 14—16 and 20—22, presenting four fingers 24, 26, 28 and 30. All of the fingers have their ends curved inwardly as at 32 and, as is clear in the showing of collar 12 by dotted lines in Fig. 6, the length of all of the slots 14—16—20—22 is substantially greater than the length of the collar 12.

25 Collar 12 has an inside diameter substantially the same as the outside diameter of the member 10 for free sliding movement on the latter throughout the length thereof between the grip 18 and the ends 32 of fingers 24, 26, 28 and 30. The collar 12 is provided with four elongated slits 38 extending longitudinally with respect thereto and equally spaced therearound to the end that one of such slits 38 is provided for each of the slots 14, 16, 20 and 22 respectively. The spacing of the slits 38 is such as to bring the same in direct registering relationship with a corresponding slot 14, 16, 20 or 22 when the collar 12 is moved toward the slotted end of the member 10, as indicated by dotted lines in Fig. 6.

Accordingly, though collar 12 is frusto-conical throughout its length, presenting a flat end 40 facing the knurled grip 18 and a flat base 42 facing the opposite end of member 10, there is presented a solid annulus 44 circumscribing the tubular member 10. By virtue of the slits 38 of collar 12, there is presented a like number of solid, wedge-shaped extensions 46 integral with annulus 44 and on that face thereof opposite to end 40.

Each extension 46 is provided with a pair of opposed, parallel side walls 48. Thus, the sides of the extension forming the slits 38 converge as the member 10 is approached. Additionally, each wedge 46 has a pair of opposed side walls 50 that converge as the inner face of wedge 46 is approached (see Figs. 5 and 7), thereby providing each slit 38 with parallel sides adjacent member 10. It is noted that in transverse cross-section, each wedge extension 46 has arcuate, concentric faces 52 and 54, the latter conforming to the shape of the finger 24, 26, 28 or 30 upon which it slides.

The slot 14 of the tubular member 10 is appreciably longer than the slots 16, 20 and 22, terminating adjacent annulus 18. An inwardly projecting lug 56 on annulus 44, slides within the slot 14, holding member 10 and collar 12 against relative rotation and permitting movement of collar 12 to the position shown in Figs. 1, 4, and in full lines in Fig. 6 near annulus 18 with slots 16, 20 and 22 out of register with their corresponding slits 38.

When the curling unit is placed in use in the manner illustrated in Fig. 1, the collar 12 is moved to that end of the member 10 adjacent the grip portion 18, the hair is gathered into a bundle 58 and the end thereof is passed through the aligned openings 14 and 16 or 20 and 22 of the member 10. The curvatures 32 of the fingers 24, 26, 28 and 30 renders such insertion of the bundle of hairs 58 relatively simple. With the ends of the hairs caught within the member 10, the operator grasps the grip 18 and rotates the member 10 on its longitudinal axis to coil the length of hairs 58 about the slotted end of the member 10, as shown in Fig. 1. After the curl has been formed in this manner, the member 10 is moved to a position substantially perpendicular to the head of the user as shown in Fig. 2, to position the curl 60 in a flat condition with respect to the head.

While holding the member 10 in such perpendicular relationship to the user's head, the collar 12 is moved longitudinally along the member 10 toward the slotted end thereof and as pressure is applied to the collar 12 to force the curl 60 flatly against the head, such curl 60 is held against displacement until pins 62 and 64 can be placed on the curl 60 to hold the same.

Pins 62 and 64 are opened in the usual manner and one leg thereof is passed on one side of the curl 60 adjacent the head, while the other leg of the pins 62 and 64 passes through the aligned slits 38 of the collar 12 and consequently through the aligned slots 14 and 16 or slots 20 and 22 as the case may be. Since the length of the pins 62 and 64 is appreciably greater than the diameter of member 10 and collar 12, the free ends of the pins 62 and 64 will project well beyond the periphery of collar 12.

As shown in Fig. 3, the pin 62 is first placed in holding relationship with the curl 60 and then the pin 64 is affixed in crossed-relationship to the pin 62. It is a simple matter for the operator

to grasp the member 10 adjacent the innermost ends of the slots of member 10 to hold the collar 12 against sliding movement toward the grip 18 and to thereby hold the curl 60 flatly against the head, while the pins 62 and 64 are moved into place.

It is to be understood that while such operation takes place, the slotted end of the member 10 is held tightly against the head. After pins 62 and 64 are positioned in the manner shown in Fig. 3, both the member 10 and the collar 12 can be entirely removed because of the fact that all of the slots 14, 16, 20 and 22, as well as the slits 38 will effectively clear the pins 62 and 64.

The advantages resulting from forming collar 12 precisely as illustrated and above described now become apparent, particularly on viewing Fig. 2 of the drawing. It is virtually impossible when compressing curl 60 tightly between base 42 and the head to prevent strands of hair from extending over the face 52 of the extensions 46. By virtue of the smooth, fully uninterrupted external surface of the collar 12, there is no chance whatsoever of entanglement to impede the complete removal of the entire unit from the curl 60. It has been found that in absence of this collar construction, raveling and twisting of the hair thereabout, makes it extremely difficult to dislodge the collar portion of the unit from the curl 60 that is bound and held tightly in place by pins 62 and 64.

The wedge-shaped slits 38, defined by inclined walls 48 and terminating in straight walls 50 facilitate the insertion of pins 62 and 64 and effectively guide the same into the slots 14—16—20—22 of member 10. And, the novel shape of collar 12 aids in handling thereof, making it easy to locate slits 38 and when the device is used without aid of a hair-dresser.

It has been found that the unit above described, can be either used by the skilled cosmetologist or by the home user and when placed in use, a plurality of curls can be formed quickly and easily with but little practice. There are no uncomfortable objects left in the curl aside from the holding pins and but one unit is necessary to form as many curls as desired. The device can be easily and cheaply manufactured and placed upon the market at an extremely low cost and need not be replaced from time to time by the user thereof because of the fact that use thereof does not damage the same in any manner whatsoever.

Many other advantages will emanate from the use of the hair curling unit forming the subject matter hereof and further, it is apparent that the same is capable of many changes and modifications and, therefore, while only one form of my invention has been illustrated and described, it is desired to be limited only by the spirit of the invention as defined by the scope of the appended claims.

Having thus described the invention what is claimed as new and desired to be secured by Letters Patent is:

1. A hair curling unit comprising an elongated member having a number of pairs of longitudinally disposed slots formed therein and extending inwardly from one end thereof, the slots of each pair thereof being diametrically opposed; and a frusto-conical collar circumscribing the member and freely slidably along the length thereof, said collar having a slit formed therein for each of said slots respectively and in register therewith when the collar is adjacent said one

end of the member, a portion of said slits being V-shaped in cross-section.

2. A hair curling unit comprising an elongated member having a number of pairs of longitudinally disposed slots formed therein and extending inwardly from one end thereof, the slots of each pair thereof being diametrically opposed; and a frusto-conical collar circumscribing the member and freely slideable along the length thereof, said collar having a slit formed therein for each of said slots respectively and in register therewith when the collar is adjacent said one end of the member, the base of said collar being flat and facing said one end of the member, a portion of said slits being V-shaped in cross sec- 15

tion and each having opposed side walls diverging as said base is approached.
